UNITED STATES PATENT OFFICE.

ALECK A. SHANKLIN, OF FAIRMONT, NEBRASKA.

PULLING MACHINE.

Application filed August 6, 1925. Serial No. 48,637.

This invention relates to certain improvements in pulling machines and it is primarily an object of the invention to provide a machine of this character adapted for use in connection with a motor driven vehicle to provide means whereby such vehicle may be readily extracted from mud, sand and the like.

It is also an object of the invention to provide a machine of this kind which is carried by the frame of the vehicle and which is in driven connection with the crank shaft of the motor.

Furthermore, it is an object of the invention to provide a machine of this character having employed in connection therewith a pulling cable or the like together with means whereby the requisite tension is maintained upon the cable during a working operation.

The invention consists in the details of construction and in the combination and arrangement of the several parts of my improved pulling machine whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a view in top plan illustrating a pulling machine constructed in accordance with an embodiment of my invention, the coacting portion of a motor vehicle being diagrammatically indicated by broken lines;

Figure 2 is a view in side elevation of my improved machine as herein set forth;

Figure 3 is a sectional view taken substantially on the line 3—3 of Figure 2;

Figure 4 is a sectional view taken substantially on the line 4—4 of Figure 3.

As disclosed in the accompanying drawings, F denotes a substantially U-shaped frame of requisite dimensions and formed preferably of channel iron. The intermediate or base member 1 of the frame is adapted to have close contact with the forward cross member 2 of the vehicle frame and maintained in such position in any desired manner as by the tie irons or straps 3 illustrated in Figure 1.

The frame F is also preferably positioned

to one side of the transverse center of the vehicle frame with the side members 4 thereof forwardly directed. These side members 4 have their outer end portions provided with upstanding posts or standards 5 also preferably of a channel type. Interposed between the forward end portions of the side members 4 and suitably attached thereto is a spacing rod 6 while directly thereabove and in parallelism therewith is a second spacing rod 7 interposed between and suitably secured to the upper portions of the uprights 5.

Freely mounted upon the rod 7 inwardly of but closely adjacent to a side member 4 is a beveled gear 8 with which meshes a beveled pinion 9 slidably mounted upon a shaft 10, said shaft 10 being rotatably supported by one of the side members 4 and disposed lengthwise thereof. This side member 4 is also provided with a suitable opening 11 to permit requisite engagement between the gear 8 and pinion 9. The pinion 9 is fixed to the shaft 10 for rotation therewith but capable of movement longitudinally thereof so that said pinion 9 may be selectively brought into mesh with the gear 8 or disengaged therefrom, the requisite movement of the pinion 9 as herein disclosed being effected through the medium of the lever 12. If desired, any suitable means as indicated at 14 may be employed to lock the lever 12 into either of its two positions.

The shaft 10 has its inner extremity suitably coupled, as at 15, with the crank shaft 16 of the motor (not shown) for the vehicle whereby the gear 8 may be driven from such motor while the opposite or outer end of the shaft 10 is provided, as at 17, with a conventional clutch member to permit the use of the well known type of starting crank.

The hub of the gear 8 at its inner side has formed therewith a pinion 18 meshing with the gear 19 carried by an end portion of a sleeve 20 freely mounted upon the second or upper rod 7. The hub of this gear 19 at the inner side thereof has also formed therewith a pinion 21 meshing with the gear 22 carried by the end portion of a sleeve 23 freely mounted on the lower rod 6 and substantially bridging the space between the pinion 18 and the second side member 4 of the frame F. The opposite end of the sleeve 23 is provided with a gear 24 meshing with a gear 25 carried by an end portion of a sleeve 26 freely mounted

on the upper rod 7 and substantially bridging the space between a side member 4 and the hub 21 of the gear 19. It is to be particularly noted that the gears 24 and 25 are of the same ratio so that during the operation of the machine the sleeves 23 and 26 will have the same peripheral speed as it is to be understood that these sleeves 23 and 26 are also of substantially the same diameter. It is to be noted, however, that the ratio of the remaining gears and pinions is such that the speed of the pinion 9 is gradually reduced so that the sleeves 23 and 26, during the operation of the machine, are caused to rotate at a relatively low speed in comparison with the rotation of the shaft 10.

Retrograde movement of the sleeves 23 and 26 is prevented through the instrumentality of the pawl or dog 27 herein disclosed as of a gravity type and which is pivotally supported by a side member 4 and has coaction with the teeth of the gear 24.

In the event the motor vehicle should become stalled, as in mud, sand or the like, a cable C is suitably anchored at a point in advance of the vehicle and said cable also wrapped a predetermined number of times around the drum 23 and then up and around the drum 26, the number of such wrappings or turns being dependent upon the load. After this arrangement of the cable C, and the pinion 9 is moved into mesh with the gear 8 and as the motor operates, the drums 23 and 26 will be caused to rotate in a manner whereby direct pull is imposed upon the frame of the vehicle resulting in the extraction of the vehicle from the mud, sand or the like. It is of particular importance that the cable C passes around the sleeve 26 as by this means requisite tension is maintained upon the cable to assure the desired pull, it being understood that as the cable passes from the drum 26 it is taken care of by a hand operation, such hand operation imposing sufficient initial tension upon the cable to assure effective operation of the machine. In view of the foregoing it will be readily understood that the sleeves 23 and 26 may also be termed drums, the upper sleeve 26 serving as a tension or friction drum.

From the foregoing description it is thought to be obvious that a pulling machine constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement

and formation of the several parts herein shown in carrying out my invention in practice except as hereinafter claimed.

I claim:

1. The combination with the frame of a motor driven vehicle and a drive shaft operated by the motor of the vehicle; of a pulling machine comprising a substantially U-shaped frame, means for connecting the intermediate portion of the U-shaped frame to the frame of the vehicle with the side members forwardly disposed, said side members at their outer end portions being provided with upstanding posts, tie rods connecting the outer end portions of the side members of the U-shaped frame and the upper end portions of the posts, a gear freely mounted on the lower tie rod adjacent to a side member of the U-shaped frame, a shaft rotatably supported by said side member and in driving connection with the gear, said shaft being in driven connection with the drive shaft of the motor vehicle, a drum freely mounted on said lower tie rod to one side of the gear, a second gear freely mounted upon the upper tie rod at a point adjacent to the first named gear and in mesh therewith, said second gear being also in driving connection with the drum, a second drum freely mounted on the upper tie rod to one side of the second gear, the ends of both of the drums remote from the gears being in driven connection, and a cable adapted to be wound on the first named drum and extended to and wrapped around the second drum, said second drum operating to maintain tension upon the cable during a working operation.

2. The combination with the frame of a motor driven vehicle and a drive shaft operated by the motor of the vehicle; of a pulling machine comprising a substantially U-shaped frame, means for connecting the intermediate portion of the U-shaped frame to the frame of the vehicle with the side members forwardly disposed, said side members at their outer end portions being provided with upstanding posts, tie rods connecting the outer end portions of the side members of the U-shaped frame and the upper end portions of the posts, a gear freely mounted on the lower tie rod adjacent to a side member of the U-shaped frame, a shaft rotatably supported by said side member and in driving connection with the gear, said shaft being in driven connection with the drive shaft of the motor vehicle, a drum freely mounted on said lower tie rod to one side of the gear, a second gear freely mounted upon the upper tie rod at a point adjacent to the first named gear and in mesh therewith, said second gear being also in driving connection with the drum, a second drum freely mounted on the upper tie rod to one side of the second gear, the ends of both of the drums remote from the gears being in driven

- connection, a cable adapted to be wound on the first named drum and extended to and wrapped around the second drum, said second drum operating to maintain tension upon the cable during a working operation, and means carried by the U-shaped frame and operable at will to make or break the operative connection between the first named gear and the associated shaft.
- 10 3. The combination with the frame of a motor driven vehicle and a drive shaft operated by the motor of the vehicle; of a pulling machine comprising a substantially U-shaped frame, means for connecting the intermediate portion of the U-shaped frame to the frame of the vehicle with the side members forwardly disposed, said side members at their outer end portions being provided with upstanding posts, tie rods connecting the outer end portions of the side members of the U-shaped frame and the upper end portions of the posts, a gear freely mounted on the lower tie rod adjacent to a side member of the U-shaped frame, a shaft rotatably supported by said side member and in driv-
- ing connection with the gear, said shaft being in driven connection with the drive shaft of the motor vehicle, a drum freely mounted on said lower tie rod to one side of the gear, a second gear freely mounted upon the upper tie rod at a point adjacent to the first named gear and in mesh therewith, said second gear being also in driving connection with the drum, a second drum freely mounted on the upper tie rod to one side of the second gear, the ends of both of the drums remote from the gears being in driven connection, a cable adapted to be wound on the first named drum and extended to and wrapped around the second drum, said second drum operating to maintain tension upon the cable during a working operation, and a pawl carried by a side member of the U-shaped frame and engageable with the adjacent drum to hold both of the drums against retrograde movement.

In testimony whereof I hereunto affix my signature.

ALECK A. SHANKLIN.
